(57) **CLAIM**

The ornamental design for a hose gripping apparatus, as shown.

DESCRIPTION

FIG. 1 is a front perspective view of the design for a hose gripping apparatus in accordance with a preferred embodiment of the present invention;

FIG. 2 is a right side view of the hose gripping apparatus of FIG. 1;

FIG. 3 is a left side view of the hose gripping apparatus of FIG. 1;

FIG. 4 is a top view of the hose gripping apparatus of FIG. 1;

FIG. 5 is a bottom view of the hose gripping apparatus of FIG. 1;

FIG. 6 is a front view of the hose gripping apparatus of FIG. 1; and,

FIG. 7 is a rear view of the hose gripping apparatus of FIG. 1.
